UNITED STATES PATENT OFFICE.

ELLIS HARTLEY, OF WHITINSVILLE, MASSACHUSETTS.

ROLL SUPPORT FOR SPINNING AND LIKE MACHINES.

Application filed May 26, 1925. Serial No. 32,919.

My invention has relation to the roll drawing mechanism of the type that is customarily used in machines for spinning worsted or silk yarns. In the present construction of machines of this class the stands supporting the drawing rolls are usually cast in one piece as shown in Figure 10 of U. S. Patent No. 765716, July 26, 1904. This construction is objectionable, as difficulty is met making the castings and properly fitting them to the framing of the machine, and furthermore, the expense of replacement in case of breakage is considerable.

In particular my invention relates to an improved construction of the drawing rolls supporting stands; and the principal object of the invention is to simplify and otherwise improve the structure of said stands whereby the expense of fitting to the machine frame and the replacement of broken parts will be reduced to a minimum.

Another object of my invention is to provide means whereby a variation in degrees of the angle of inclination of roll supports may be readily made when desired.

A further object of my invention is to provide a simple and inexpensive construction of a roll supporting stand whereby the amount of space between the front and back drawing rolls may be increased whenever it is desired to operate on a longer length of fibre than the maximum length for which the machine was built.

With the above and other objects in view which will appear as the description proceeds, my invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is fully described in the following specification, illustrated by the accompanying drawings, in which like reference characters designate like parts.

In the drawings:

Figure 1 is a partial end elevation of a worsted spinning frame showing my improvement thereon. Figure 2 is a plan view of a frame with parts omitted in order to clearly show the present invention. Figure 3 is a side elevation of my improved roll support. Figure 4 is a plan of the same. Fig-

ure 5 is a sectional view on line 5—5 of Figure 4. Figure 6 is a front elevation of the roll support base. Figure 7 is a side elevation of the back roll slide and Figure 8 is a front elevation of the same. Figure 9 **60** is a front elevation of the back roll slide fastener and Figure 10 is a side elevation of the same. Figure 11 is an end view of the carrier roll slide and Figure 12 is a front elevation of the same. Figure 13 is a **65** view of the carrier roll slide clamping bolt and Figure 14 is its clamping nut.

Having reference to the drawings, 1 designates one of the end frames of the machine, (the opposite end frame not shown in the drawings), 2 is a beam extending longitudinally at the front of the machine and is fixedly connected to the end frames of the same. The beam 2 in combination with the creel board 3 fixed to the top of the machine **70** support a plurality of stands or supports on which the bearings of the drawing rolls, held in suitable holders, are mounted either in a fixed position or slidably thereon. Each stand or support is made up of four separate members or sections, detachably connected together, comprising a front member 4, a rear member 5, an intermediate member 6 and a base member 11. The upper part of the front member 4 serves as a holder for the bearing 12 of the front roll 13, the lower part of said member being provided with trunnions 7 slidably mounted in a hole or bearing in the web of the member and positioned therein by a set screw 8. These trunnions are swingably in bearings 9 and 10 in the upright lugs integral with the base member 11 which is securely mounted on the rail 2. In a boss 14 on the rear part of the front member 4 a hole or seat is located in which the front end of the intermediate member 6 is seated and detachably secured therein preferably by the set screw 15.

The intermediate member 6, supporting the bearing slides of the carrier and back rolls, is made preferably of a bar of cold rolled metal of a circular cross section cut in varying lengths thus providing changeable means whereby the space between the front and back rolls may be increased so **100** that the rolls will properly function on a length of fibre greater than the maximum for which the machine was built. This feature of my improved roll stand or support has met with favorable response from **105** yarn **110**

manufacturers as its adoption in place of the old type of one piece roll support results in substantial savings in expenses of new parts and labor required in changing the machine 5 over.

The carrier roll bearing slides 16 and the back roll bearing slides 17 are provided with arcuate shaped bases conforming to the curvature of the surface of the intermediate 10 member 6 on which they are slidably mounted. The positions of the carrier and back rolls may be varied in their relation to each other by means of manually operated shafts 18, extending longitudinally beneath the intermediate member 6, with pinions 19 fixed thereon and coacting with racks 20 cut in the lower sides of said intermediate member. Each carrier roll bearing slide 16 is fastened in its proper position on the intermediate member 6 by means of a screw 21 threaded into a nut 22 slidably mounted in the dovetailed slot 23 cut in the upper surface of the intermediate member 6. Each back roll bearing slide 17 is held in position 15 on the intermediate member by an eye bolt formed with a ring 24, embracing the intermediate member 6, and a stem 25 which is threaded into a clamping nut 26 coacting with the upper surface of the back roll bearing slide.

The rear member 5 supporting the rear end of the roll stand or support is detachably connected to the rear end of the member 6 preferably by the set screw 27, and is 35 adjustably mounted on a hanger 28 fixedly connected to the creel board 3. The adjusting slot 29 in the hanger 28 is formed on the arc of a circle concentric with the centre of the trunnions 7 whereby the proper inclination 40 of the roll support may be obtained; when this is accomplished the member 5 and the hanger 28 are tightly clamped together by the bolt 30 passing through the slot 29 and threaded into the member 5.

45 By the construction above described, the fitting of the roll supports to the framing of the machine is easily and quickly accomplished; in case of breakage the expense of replacement is greatly reduced in comparison with the use of the ordinary type of one piece construction of roll supports, and the machine can be readily adapted to spin varying lengths of fibre by the use of different lengths of the intermediate member.

55 It is sometimes found desirable to simultaneously vary the inclination of all of the roll supports which my invention readily accomplishes by means of arcuate racks 31 attached to the support members 5 and cooperating with pinions 32 fixed to a manually operated shaft 33 extending longitudinally beneath the creel board 3. By this construction the operative, desiring to change the inclination of all of the roll supports, loosens 60 the clamping bolts 30 and twists the shaft 33

one way or the other until the desired inclination is obtained, then retighten the bolts 30. The shaft 33 may be turned by any suitable manually operated means preferably I make use of a gear 34 fixed to shaft 33 70 and cooperating with a worm 35 manually rotated by a handle on shaft 36.

I claim:

1. As a new article of manufacture, a sectionally constructed stand for supporting a plurality of drawing roll bearings, comprising a base member, a front roll bearing supporting member mounted on said base member, a rear member for supporting the rear end of the stand and changeable means for varying the space between the front roll and back roll, said means supporting the bearings of the carrier and back rolls and detachably connected to the front and rear members of the stand. 75 80 85

2. As a new article of manufacture, a sectionally constructed stand for supporting a plurality of drawing roll bearings, comprising a base member, a front roll bearing supporting member swivelly mounted on said base member, a rear member supporting the rear end of the stand and changeable means for varying the space between the front roll and back roll, said means supporting the bearings of carrier and back rolls and detachably connected to the front and rear members of the stand. 90 95

3. As a new article of manufacture, a sectionally constructed stand for supporting a plurality of drawing roll bearings, comprising a base member, a front roll bearing supporting member swivelly mounted on said base member, a rear member supporting the rear end of the stand and a changeable intermediate member detachably connected to the front and rear members and made in lengths to suit the varying spaces required between the front roll and back roll. 100 105 110

4. As a new article of manufacture, a sectionally constructed stand for supporting a plurality of drawing roll bearings, comprising a cast metal base member, a front roll bearing supporting member of cast metal swingably mounted on said base member, a cast metal rear member for supporting the rear end of the stand and a changeable intermediate member of round cold rolled steel cut in different lengths for the varying spaces between the front roll and back roll and detachably connected to said members. 115 120

5. In a machine of the character specified having a series of drawing rolls rotatable in bearings mounted on a sectionally constructed stand comprising a base member fixed to a stationary part of the machine, a front roll bearing supporting member swivelly mounted on said base member, a rear member adjustably connected to a stationary part of the machine, a changeable intermediate member variable in length de- 125 130

tachably connected to said front and rear members, and manually operated means for varying the angle of inclination of the roll bearing supporting stands.

5 6. In a machine of the character specified, having a series of drawing rolls rotatable in bearings, in combination, a sectionally constructed supporting means for said bearings comprising a base member fixed to a stationary part of the machine, bearings supported on said base member, a front roll bearing supporting member, trunnions fixedly connected to said member and swingably mounted in the bearings supported on the base member, a rear member adjustably connected to a stationary part of the machine, a changeable intermediate member variable in length detachably connected to the front roll bearing supporting member 10 and rear member, an arcuate rack fixedly connected to said rear member and concentric with the trunnions on the front roll bearing supporting member, a shaft extending longitudinally of the machine and held 15 in bearings fixed to a stationary part of the machine, a pinion fixed to the shaft and coacting with said rack, and manually operated means for imparting rotary motion to said shaft whereby the angle of inclination 20 of the roll bearings supporting means may be varied.

7. In a machine of the character specified, a roll bearing supporting means comprising a base member fixed to a stationary part of the machine, a front roll bearing supporting member mounted on said base member, a rear member adjustably connected to a stationary part of the machine, a changeable intermediate member of a circular cross-section 25 detachably connecting the front roll bearing supporting member and rear member, carrier and back roll bearing stands slidably mounted on said intermediate member, arcuate shaped bases for said bearing stands

and means for fastening said stands to said intermediate member.

8. In a machine of the character specified, a roll bearing supporting means comprising a base member fixed to a stationary part of the machine, a front roll bearing supporting member mounted on said base member, a rear member adjustably connected to a stationary part of the machine, a changeable intermediate member of a circular cross-section 50 detachably connecting the front roll bearing supporting member and rear member, carrier roll bearing stand slidably mounted on said intermediate member, arcuate shaped base for said bearing stand 55 loosely mounted on the upper surface of the intermediate member, a dovetailed slot milled in upper surface of said intermediate member, a nut slidably mounted in the slot, and a screw coacting with the nut and the 60 base of the stand thereby locking the carrier roll stand to the intermediate member.

9. In a machine of the character specified, a roll bearing supporting means comprising a base member fixed to a stationary part 70 of the machine, a front roll bearing supporting member mounted on said base member, a rear member adjustably connected to a stationary part of the machine, a changeable intermediate member of a circular cross-section 75 detachably connecting the front roll bearing supporting member and rear member, back roll bearing stand slidably mounted on said intermediate member, arcuate shaped base for said bearing stand 80 loosely mounted on the upper surface of the intermediate member, an eye-bolt embracing the intermediate member, and a nut coacting with the eye-bolt and the upper surface of the back roll bearing stand whereby said 85 stand is fastened to the intermediate member.

In testimony whereof, I have signed this specification.

ELLIS HARTLEY.
